Patented Apr. 8, 1913.

UNITED STATES PATENT OFFICE.

HUGO HANS HERMANN VON PEIN, OF HAMBURG, GERMANY, ASSIGNEE TO THE FIRM
OF HUGO V. PEIN, OF HAMBURG, GERMANY.

DEVICE FOR CARBONATING LIQUIDS.

1,058,383.

Specification of Letters Patent.

Patented Apr. 8, 1913.

Application filed November 8, 1912. Serial No. 729,822.

To all whom it may concern:

Be it known that I, HUGO HANS HERMANN VON PEIN, a citizen of the United States of Venezuela, and resident of Hamburg, Germany, have invented a new and useful Device for Carbonating Liquids, of which the following is a specification.

The device forming the subject matter of this invention is a carbonating device of such kind, in which there is a mixing vessel, into the upper part of which the liquid to be impregnated and also the gas is led, so that merely that quantity, which is to be tapped or given off is mixed or impregnated.

It has been found out, that the impregnated liquid will have a perfectly pure taste, when the air contained in the mixing vessel and the air accompanying the liquid is expelled as soon as the gas and the liquid are introduced and when care is taken to avoid the air from coming in contact with the impregnated liquid. This is arrived at by arranging above the mixing vessel and separate from it an air reservoir, which is connected with the mixing vessel merely by a narrow channel and provided with a non-return valve and with an air escape valve.

The air gathers in the upper part of the vessel on account of its being lighter than the liquid and therefore can easily be let off into the air reservoir, the narrow channel preventing the expelled air from coming into contact with the impregnated liquid. The non-return valve prevents the air from flowing back into the mixing vessel. The air escape valve is adjusted to the same pressure as or to a somewhat higher pressure than the pressure of the inflowing gas, so that air escapes, when there is an excess of pressure owing to an abundant delivery or passage of air.

In the drawing Figure 1 is an elevation partly in section of a tapping device to carry out this invention by way of example. Fig. 2 shows the tank for receiving the expelled air in sectional elevation to a larger scale.

The tank or container *a*, into which the liquid is filled, is closed and provided with an upright inner tube *b*, to which is connected the outer tube *c*, leading to the upper part of the mixing vessel *d* through an atomizer *e*, the lower part of the mixing vessel *d*, which is preferably of glass is provided with a tapping cock. The gas (such as carbonic acid) used to expel the liquid from the

container *a* into the vessel *d* and to impregnate the same in the latter, is contained in a flask *f* and led into the container *a* by the pipe *g* and into the vessel *d* by the pipe *h*. By the aid of pressure reducing valves *g'*, *h'* the pressure in the pipe *h* will be reduced to somewhat less than the pressure in the pipe *g* to allow the liquid to be driven from the container *a* into the vessel *d* filled with gas.

Outside and above the vessel *d* a chamber or tank *i* is provided for gathering the air expelled from the liquid in the vessel *d*. This tank *i* is connected with the vessel *d* by a pipe *l* and passage *n* and is provided with a non-return valve *m* and air escape valve *m'*. The pipe *h* connects the pipe *l* with the flask *f*. The passage *n* which leads from the pipe *l* to the inside of the vessel *d* is very narrow.

From the description given above it will be seen that gas can always freely enter the vessel *d*. The valve or cock *h* of the pipe *c* is opened, whereby liquid can enter the vessel *d*, at the same time being well atomized by the nozzle or atomizer *e*. This has the effect, that the liquid is well spread and easily and abundantly saturated with gas, the atmospheric air being expelled and driven by way of the narrow channel or passage *n* into the tank *i*, from where it can escape through the air valve *m'*.

If desired the liquid may be derived from a pressure pipe or common water main pipe, in which case the container *a* and pipe *g* may be dispensed with.

I claim:

1. A device for carbonating liquids comprising a mixing vessel, an air chamber, a channel connecting the upper part of the vessel with the chamber, a pipe for conducting liquid to the upper part of the vessel, a pipe for conducting gas to the vessel above liquid and communicating with the air chamber, and an air escape valve in the latter.

2. A device for carbonating liquids comprising a mixing vessel, an air chamber, a narrow channel connecting the lower part of the chamber with the upper part of the vessel, a pipe for conducting liquid to the upper part of the latter, a pipe for conducting gas to the vessel above the liquid and communicating with the air chamber, and an air escape valve in the latter.

3. A device for carbonating liquids comprising a mixing vessel, an air chamber, a

narrow channel connecting the lower part of the chamber with the upper part of the vessel, a pipe for conducting liquid to the upper part of the latter, a pipe for conducting 5 gas to the vessel above the liquid and communicating with the air chamber, an air escape valve in the latter, and a non-return valve in the air chamber.

4. A device for carbonating liquids, comprising a mixing vessel, an atomizer in the 10 upper part thereof, a pipe for supplying liquid to the vessel through the atomizer, an air chamber, a narrow channel connecting the upper part of the vessel with the 15 lower part of the air chamber, a gas supply pipe communicating with the air chamber and with the vessel above said channel and above the liquid supply pipe, and a spring controlled escape valve in the air chamber.

5. A device for carbonating liquids comprising a mixing vessel, an atomizer in the upper part thereof, a pipe for supplying liquid to the vessel through the atomizer, an air chamber, a narrow channel connecting the upper part of the vessel with the 25 lower part of the air chamber, a gas supply pipe communicating with the air chamber and with the vessel above said channel and above the liquid supply pipe, a spring controlled escape valve in the air chamber, a 30 non-return valve opening into the latter above the gas supply pipe, and means for regulating the pressure in said supply pipes.
